CLAIM

The ornamental design for a bottle, as shown and described.

DESCRIPTION

FIG. 1 is a top perspective view of a first embodiment of a bottle, showing my new design.

FIG. 2 is a partially enlarged view thereof, taken from FIG. 1.

FIG. 3 is a front view thereof.

FIG. 4 is a rear view thereof.

FIG. 5 is a first side view thereof.

FIG. 6 is a second side view thereof.

FIG. 7 is a top view thereof.

FIG. 8 is a bottom view thereof.

FIG. 9 is an exploded top perspective view thereof.

FIG. 10 is an exploded front view thereof.

FIG. 11 is a cross-sectional view thereof, taken along line 11-11 in FIG. 1.

FIG. 12 is a top perspective view of a second embodiment of a bottle, showing my new design.

FIG. 13 is a partially enlarged view thereof, taken from FIG. 12.

FIG. 14 is a front view thereof.

FIG. 15 is a rear view thereof.

FIG. 16 is a first side view thereof.

FIG. 17 is a second side view thereof.

FIG. 18 is a top view thereof.

FIG. 19 is a bottom view thereof.

FIG. 20 is an exploded top perspective view thereof.

FIG. 21 is an exploded front view thereof.

FIG. 22 is a cross-sectional view thereof, taken along line 22-22 in FIG. 12.

FIG. 23 is a top perspective view of a third embodiment of a bottle, showing my new design.

FIG. 24 is a partially enlarged view thereof, taken from FIG. 23.

FIG. 25 is a front view thereof.

FIG. 26 is a rear view thereof.

FIG. 27 is a first side view thereof.

FIG. 28 is a second side view thereof.

FIG. 29 is a top view thereof.

FIG. 30 is a bottom view thereof.

FIG. 31 is an exploded top perspective view thereof.

FIG. 32 is an exploded front view thereof.

FIG. 33 is a cross-sectional view thereof, taken along line 33-33 in FIG. 23.

FIG. 34 is a top perspective view of a fourth embodiment of a bottle, showing my new design.

FIG. 35 is a partially enlarged view thereof, taken from FIG. 34.

FIG. 36 is a front view thereof.

FIG. 37 is a rear view thereof.

FIG. 38 is a first side view thereof.

FIG. 39 is a second side view thereof.

FIG. 40 is a top view thereof.

FIG. 41 is a bottom view thereof.

FIG. 42 is an exploded top perspective view thereof.

FIG. 43 is an exploded front view thereof; and,

FIG. 44 is a cross-sectional view thereof, taken along line 44-44 in FIG. 34.

The dot-dot-dash broken lines are included to show partially enlarged views only and form no part of the claimed design.
